CARWASHING APPARATUS

John G. Friers, Derby, Conn.

Application May 27, 1952, Serial No. 290,273

9 Claims. (Cl. 134—123)

The present invention relates to carwashing apparatus, and more particularly to the type of washing apparatus which includes a spraying frame from which jets of water or soapy solution may be sprayed onto an automobile.

Carwashing apparatus have been proposed in which an inverted, substantially U shaped frame is guided along a pair of spaced tracks, the car to be washed being placed between the tracks. The frame is then pushed or driven along the length of the car—or the car is driven back and forth under the frame. Different supply pipes for soapy solution, and for rinsing or wetting have usually been used. This arrangement has the disadvantage that usually a pair of permanent tracks have to be laid in or on the garage floor, which necessitates fairly expensive cement work; further, that the car has to be brought to the washing station; that only one car can be washed at a time; and also, that the car has to be located fairly accurately between the spaced tracks to prevent damage to the car by the spraying frame. A further disadvantage of such an apparatus is that it takes up considerable space within the garage itself, and that fairly extensive and expensive plumbing connections have to be made.

It is an object of the present invention to provide a carwashing apparatus which requires no outside plumbing installation, is entirely self-contained, and is independent of any installed tracks.

It is a further object of the invention to provide a carwashing apparatus which may be brought to the car, wherever it may be located—rather than the car to the apparatus—and which is portable and can readily be moved about a garage, gasoline station, or parking area.

It is still another object of the invention to provide means which will guide the carwashing apparatus alongside the car to be washed, thereby preventing damage to the same, which means may be removably located with respect to the car. It is yet another object to provide a carwashing apparatus which is capable of washing a plurality of cars in a row, such as may be parked in a parking lot, removed from any permanently installed plumbing or water supply.

It is still another object of the invention to provide a carwashing apparatus in conjunction with a dolly, which is self powered and includes the necessary means to wash cars, but which also may be used as a portable source of power about a garage or gasoline station, as a portable compressor or pump, and to which a small snowplough may be attached for power ploughing, or which may be used as a small tractor to pull equipment, or disabled cars, at low speeds.

It is yet another object of the invention to provide means permitting a spraying frame to be swingably mounted and connected to the apparatus. Such a spraying frame should be capable of being taken apart and provided with interchangeable parts of different sizes for use with passenger cars, trucks, and heavy equipment.

According to the present invention, I provide a carwashing apparatus in which a frame has a plurality of wheels mounted thereon, to support the frame for move-

ment over a surface, such as the garage floor; the frame carries a motor, a pump connected to the motor, a tank to hold washing water, and an upright pipe, having spraying nozzles screwed therein. Pipes are provided to connect the tank to the pump, and the high pressure side of the pump to the upright pipe, which preferably is connected to an inverted, substantially U-shaped spraying frame.

A container for cleaning substance (preferably a liquid detergent) is mounted on the frame, and has a pipe connection to the piping from the main tank to the spraying frame. The motor is also preferably connected to a small transmission, having a forward, neutral, and reverse position, and a connection is made from the transmission to the wheels, so that the wheels, and with it the whole apparatus, may be power driven in a selected direction.

According to a feature of the invention, the fluid tank is so located on the frame that its weight counterbalances the weight of the spraying frame, thereby permitting the portion of the spraying frame distant from the tank to be entirely supported by the support frame, and making the location of a track to support this distant portion unnecessary.

Still another feature of the invention contemplates the use of wheel guide means to guide the wheels of the support frame (which forms what might be termed a dolly, or washing cart), so that the dolly, and the spraying frame secured thereto, are always correctly spaced from the car to be washed. These guide means are preferably provided with a locating means, such as a wheel shoe, which may be placed against the wheels of the car to be washed, so that the dolly wheel guide means are correctly spaced with respect to the car.

Yet another feature of the invention contemplates the provision of a spraying frame consisting of a single pipe having spraying nozzles secured therein, which frame is swingably mounted on the dolly so that it may be folded against the dolly, thereby taking up little space in a garage. The frame is preferably so constructed as to be separable into several sections, so that it may be taken apart easily and stored disassembled.

Still other features of the invention relate to structures used in the construction of the dolly, and the spraying frame, and the elements thereof.

The novel features which are considered as characteristic for the invention are set forth in particular in the appended claims. The invention itself, however, both as to its construction and its method of operation, together with additional objects and advantages thereof, will best be understood from the following description of specific embodiments when read in connection with the accompanying drawings, in which:

Fig. 1 is a top plan view of the apparatus in position to wash a car;

Fig. 2 is a side view of Fig. 1;

Fig. 3 is a rear view of Fig. 1;

Fig. 4 is a side view, partly in section, showing the water supply connection to the tank of the apparatus;

Fig. 5 is an elevational view, partly in section, showing the fluid supply connection to the spraying frame;

Fig. 6 is a top sectional view taken along line 6—6 of Fig. 5;

Fig. 7 is an elevational view, partly in section, showing a wheel connection to an axle;

Fig. 8 is a side view of Fig. 7;

Fig. 9 is a perspective view showing the connection of the wheel guides;

Fig. 10 is a sectional view taken along line 10—10 of Fig. 9;

Fig. 11 is a perspective view of a wheel guide, part of it being broken away;

Fig. 12 is a cross-sectional-elevational view of a one-way clutch;

Fig. 13 is a detail view of the spraying frame, in elevation, showing the splash guards and stiffening members;

Fig. 14 is a sectional view taken along line 14—14 of Fig. 13; and

Fig. 15 is a schematic plumbing diagram of an alternate form of pipe connection.

Referring now to the drawings, and more particularly to Figs. 1 to 3, 1 generally indicates the car to be washed. Two wheels of the car are indicated at 2a and 2b, since the apparatus is designed to cooperate with aligned wheels of the car to be washed. 3 generally indicates a dolly, or small cart, having wheels 4, 5, 6, and 7 located on opposite sides, and at opposite ends of the dolly 3. The dolly is built up of a frame 8 and is preferably provided with a platform, or support 9, on which the various elements of the apparatus may be conveniently mounted. Secured to the frame is a handle 8' so that the dolly may be conveniently manipulated. A motor 10 is mounted on the platform 9 of the dolly 3; the motor is connected to a pump 11 by any suitable and well known means, such as a flexible coupling. A gearbox 12 is connected to the motor drive shaft, for example by being secured to the main shaft of the pump 11, as shown. The gearbox preferably has a high speed reduction, and is provided with a shift lever having a handle 13 permitting shifting the gears to a forward (F), neutral (N) and reverse (R) direction. At the output side of the gearbox 13, a sprocket wheel 60 is mounted and connected as will appear hereafter.

A tank 14 (which may be a standard 55 gallon drum) is mounted on platform 9 in any suitable and well known manner, for example by welding, by a circumferential strap, or the like. This tank may be filled in any suitable manner, e. g., by filling it with a garden hose. If it is desired to fill the tank while the dolly is in motion, a hose may be connected to a filler pipe 17 (see Fig. 4) which is placed within an inlet pipe 15 secured to the tank 14. Inlet pipe 15 is split at the far end thereof, as shown at 16, and a tightening nut 18 is placed over the split end. When it is desired to store the machine, filler pipe 17 is pushed into inlet 15 as far as it will go, thereby taking up no space beyond the outline of the dolly; however, when the dolly 3 is moving, a hose connected to pipe 17 when pushed in might get tangled with the wheels 6 and 7 of dolly 3, unless a rigid clearance member is provided. When filler pipe 17 is extended, a hose will clear the wheels of the dolly.

The tank 14 is connected to the pump by means of a pipe 20. A soap vessel, or detergent container 21 is secured to the platform in any suitable manner and connected to the pipe 20 by means of a supply pipe 22 and an injector connection 24. A shutoff cock 23 is placed in pipe 22 to control the flow of soap or detergent, or other cleaning substance. The cleaning substance may be a liquid, and may be gravity fed as shown in Fig. 2.

The car 1 is wetted and washed by a spraying frame 25. This frame essentially consists of a pipe having nozzles 26 screwed therein. The frame 25 is secured to the dolly 3 at one side of the dolly. An upright fastening member 27 is mounted on the frame of the dolly 3 and the frame 25 is secured to this fastening member 27 by any suitable means, for example by straps encircling the frame 25 and welded to member 27. The frame 25 is preferably secured so as to be swingable about its upright portion 28 adjacent the member 27, so as to take up less space in a garage. In Fig. 1, 25 indicates in dotted lines the position of frame 25 when swung into storage position. The frame 25 is preferably made of two sections; one, consisting of an upright pipe portion 28 and a horizontal pipe portion 29a; the other of a generally horizontal pipe portion 29b, and a depending pipe portion 31. The two sections are joined together

by a union 30. In order to take mechanical strain off the cooperating faces of the union, I prefer to make the pipe portion 29b of smaller diameter than the pipe portion 29a. The part of the union secured to the smaller pipe may then be bored out so that pipe portion 29b may extend beyond the face of the union part and can slide into the pipe portion 29a up to the first nozzle adjacent the union. The union may also be located on the upright portion 28 of the pipe frame 25, and the horizontal portion 29 made in one piece. By having various sizes of pipe frames it is therefore possible to wash small cars, as well as large trucks, and still have a spraying frame which is close enough to the surface of the car to be washed for efficient cleaning. The spraying frame 25 is preferably made of lightweight pipe, such as aluminum, and it can be entirely self supporting. It is to be noted that the weight of the spraying frame 25 can be entirely balanced by the weight of the tank. When a standard 55 gallon steel drum is used it must be so mounted that its center of gravity falls between a median line of the dolly and the side opposite the fastening member 27, in order to balance a spraying frame of standard 1" galvanized iron pipe sufficiently large to clear the largest passenger cars currently made. If the spraying frame is made of aluminum pipe of similar size, no unbalance of the dolly will result even if the tank 14 is mounted centrally of the dolly 3. When computing the amount of off-center mounting of tank 14, the weight of the water in the spraying frame 25 has to be considered, as well as the weight of the frame itself.

The dolly 3, together with the spraying frame 25, is guided along the length of the car 1 by means of wheel guides 35. These wheel guides are preferably made in sections, 35a, 35b, 35c, etc. of suitable length, so as to be easily portable. Referring now particularly to Figs. 9 to 11, each section of the wheel guide is preferably made of a pair of angle irons 36a, 36b, connected together by straps 37. The wheels of the dolly 3 can then ride on the surface on which the wheel guides are placed. The wheel guides are joined loosely together so as to accommodate uneven surfaces, such as would be encountered at parking areas. The angles 36a, 36b, are notched as at 45, near one end, a plurality of notches being preferably provided so that the total length of the wheel guide may be made longer or shorter. The other end of each section is provided with an extension 43, set off, as at 44, and provided with studs 46 fitting into the notches of the next adjacent section.

In order to locate the wheel guide 35 with respect to the car 1, one, or several of the sections are provided with wheel shoes fitting against the wheels 2a, 2b of car 1. These wheel shoes preferably have a forked section 38, secured to a support member 39 spacing the fork 38 from a fastening plate 40 which may be secured to one of the wheel guide angles, 36a. The wheel shoes are preferably adjustable along the length of the wheel guide, to accommodate cars or trucks of differing wheel bases; a bolt and nut combination, slidable in a notch 42 and having a bolt 41 secured to the fastening plate 40 forms a simple means of mounting the wheel shoes adjustably on the wheel guide.

As noted above, the spraying frame 25 is preferably mounted on the dolly 3 to swing from an extended position (shown in solid lines in Fig. 1) to a storage position (shown at 25' in dotted lines in Fig. 1). As shown in Fig. 1, a pipe 47, having a valve 48 interposed therein, connects the high pressure side of pump 11 to the spraying frame 25. The connection of the pipe 47 to the upright portion 28 of the spraying frame 25 is illustrated in detail in Figs. 5 and 6.

The upright portion 28 of the pipe has a hole 49 drilled into the sidewall. A sleeve 50 of a resilient material, such as rubber, having a hole 51 therein, is passed over the pipe 28 so that the holes 49 and 51 are in registration. A split sleeve 52 is then placed over the resili-

ient sleeve 50. The split sleeve has an outlet stub pipe secured thereto. The outlet stub pipe 53 is then secured by means of a nut 54 to pipe 47 as is well known in the plumbing art. The split sleeve 52 has a clamping extension 55, and can be tightened together by screws 55'. When the screws 55' are loose, the frame 25 can be swung readily from extended into storage position. Tightening of the screws 55' when the frame is in extended position will line up the outlet stub 53, holes 51 and 49, and permit flow of fluid from the pipe 47 into the frame 25, without danger of leakage, due to resilience of the interposed sleeve 50. The split sleeve may be secured to the upright member 27 of the dolly 3, for example by means of screws 56, and form in itself an attaching means for the frame to the dolly.

The dolly 3 may be pushed along the length of the car 1, or it may be driven along under its own power. The sprocket wheel 60, connected to the gear box 12 (which is connected to the motor 10) drives a sprocket chain 61. Chain 61 is in engagement with a second sprocket wheel 62 which is fast on an axle 64, for example by means of set screw 63. The axle 64 is secured to frame 8 by means of bearing 65 and connects the two wheels 4 and 6 of dolly 3. Referring particularly to Figs. 7 and 8, I have there shown a simple driving connection of the wheel 6 to the axle 64. The wheel 6 is provided with a hub 66 and a rim support 67, having holes 67' therein. The hub is freely rotatable on the shaft 64; an attaching member having a hub 68 is located on the shaft adjacent the wheel 6. The attaching member is provided with a radially extending strap 69, having axially extending pins 70 secured thereto, fitting into the holes 67'. Both the shaft and the attaching member have a radial hole bored therethrough, through which a cotter pin is passed, connecting the shaft 64 and the hub of the attaching member, 68, together, as shown at 71. The pins 70, engaging the wheel 6, will then drive the same, when the shaft or axle 64 is being driven.

The motor 10 driving the pump and the dolly may be either a gasolene or electric motor, two horsepower being an adequate size. For some purposes it may be preferred to use a gasolene motor, since it is entirely independent of any cables or power connections and the dolly may then be used as a small tractor. Small gasolene engines are usually started by means of a starting rope, as is well known. To facilitate starting such a motor, and winding the rope around a starting drum, I provide a one-way clutch, particularly illustrated in Fig. 12 of the accompanying drawings. 80 is a central shaft which may turn in either direction; a driven shaft (which will turn in one direction only) 81 has an axial bore drilled therein, and the shaft 80 is placed into the bore, which should be of such size that shaft 80 can just turn freely within shaft 81. The shaft 81 has a depression, or relief formed therein, as shown at 83. A substantially tangential bore extends from the outside of shaft 81 to the depression, as shown at 82. The outside end of this bore 82 is tapped to receive a holding screw 86. A roller 84 (which may be a small ball, or a rolling pin, depending on the axial length of the depression 83) is placed into depression 83, between the shafts 81 and 80. A spring 85 holds the roller 84 in position and urges roller 84 to a location where it will engage both shafts. It is to be noted that the depression or relief 83 is so formed as to merge smoothly into the circular contour of the bore of shaft 81. When the central shaft 80 turns in a counterclockwise direction, it will take along the roller 84, which will become wedged between the shafts 80 and 81, thereby turning shaft 81. However, when shaft 80 is turning in a clockwise direction, roller 84 will turn and roll away from the position where it becomes wedged between shafts 80 and 81, and shaft 81 will remain stationary. The small holding screw 86 may be screwed in or out of bore

82, thereby adjusting the tension of spring 85 and controlling the backlash of the one-way clutch.

The depression may also be formed in the central shaft, and the outside shaft 81 may be left round, or the depression may be formed in both shafts, 80 and 81, as desired. In such cases the bore 82 has to be formed in the central shaft, and care must be taken in assembling the shafts together.

The nozzles 26 screwed into the spraying frame have generally a very small central duct through which the spraying water, or washing solution, is being forced. Small solid particles which may become lodged near the outside of the nozzles may deflect the stream of water towards undesirable directions. In order to keep the streams of water from the nozzles always directed on the car, I prefer to enclose the pipe with a baffle, or splash-guard, 90. Referring now to Figs. 13 and 14, the splash-guard 90 essentially consists of sheet metal which has a trough shaped portion 92, partly encircling the pipes 28, 29a, 29b, and 31, and two projecting flanges 93, as particularly illustrated in Fig. 14. The baffle 90 is held on the pipes by means of screws 91, clamping the trough shaped portion 92 securely around the pipes. The baffles may be made either in small, individual guards located over the pipes in the region of the nozzles, or they may be made substantially continuous along the lengths of the pipe sections. At the junction of the horizontal and the vertical sections, the splashguards may then be interconnected as shown at 94 and 95 (Fig. 13), thereby adding to the stiffness and rigidity of frame 25.

In Fig. 15 I have illustrated a modified form of pipe connection which is also suitable. The main water valve, 48, is here placed in pipe 20 leading from the tank 14 to the pump 11; the detergent solution is injected at point 97, at the high pressure side of the pump. If this arrangement is used, a suction-injection device (such as a venturi tube, for example) is necessary in order to prevent the water under pressure from escaping into the detergent vessel 21.

The operation of my apparatus is as follows: The wheel shoes are placed along aligned wheels of the car to be washed, with their forked section 38 against the wheels 2a and 2b. The wheel guide sections 35 are then assembled as shown in Fig. 9, and secured to the wheel shoes. In the meanwhile, the tank 14 of the dolly can be filled. The dolly is then brought to the car, and wheels 4 and 5 thereof substantially aligned with the wheel guide. Valves 23 and 48 are closed, the handle 13 set on neutral (N), and the motor started. The spraying frame is then extended to the solid line position shown in Fig. 1, valve 48 is opened (valve 23 remains closed) and the handle 13 moved to engage the gearing in the appropriate direction to drive the dolly 3 along the length of the car 1 to wet the same. A detergent (which is preferably liquid) is then placed in vessel 21. The valve 48 is partially closed (less pressure and less water being necessary for the soaping operation) and valve 23 opened. The gear-shift handle 13 is then moved in the direction opposite to its previous setting, and the dolly 3 will travel again along the length of car 1, soaping the car by the soapy spray from frame 25. Then the direction of travel of the dolly again is reversed, valve 48 opened fully, and valve 23 closed, and the car is rinsed. It is usually advantageous to permit the dolly to travel back and forth along the car when rinsing to wash off any soap or dirt which may lodge in crevices or moldings.

I have found that a 55-gallon drum is sufficient to wash one car, about 40 to 45 gallons of water being necessary for one washing operation. About 1½ pints of a commercial detergent, such as "Immunol Solvent" (manufactured by the Haas Miller Corp., Philadelphia, Pa.) are sufficient for thorough soaping.

The dolly itself may be quite small, about 2½ ft. wide by 4½ ft. long, and about 3 ft. high. The spraying frame should have a minimum horizontal clearance of

7½ ft., and may be about 6 to 8 ft. high, if it is intended to wash the now current passenger automobiles. By making the track guide sections about 5 ft. long, and of light weight metal, they can easily be stored on top of the dolly.

The apparatus is entirely independent of any permanent plumbing connections, and by placing a larger tank on the dolly, a number of cars in a row (such as would be found on a parking place) can be washed, without disturbing their position, and without driving them to a predetermined washing station. The wheel guides will keep the dolly and the frame properly spaced from the cars to be washed, and will guide the dolly along the cars, even if the surface on which the dolly runs is uneven. If desired, the inlet pipe 17 may be extended, and the tank may be continuously filled while the apparatus is washing. This may prove advantageous, where the source of water can supply more water than is needed for soaping, but not enough for wetting, and rinsing.

It will be understood that each of the elements described above, or two or more together, may also find a useful application in other types of washing apparatus, differing from the type described above.

While the invention has been illustrated and described as embodied in a small, movable carwashing apparatus, it is not intended to be limited to the details shown, since various modifications and structural changes may be made. By applying current knowledge, the invention, including the features that fairly constitute essential characteristics of the generic and specific aspects thereof, may be adapted to various applications and such adaptations should and are intended to be comprehended within the meaning and range of equivalence of the following claims.

I claim:

1. In washing apparatus for bulky objects, a liquid supply having an outlet; means for supplying liquid at said outlet under pressure; and a spray frame connected to said outlet and comprising a pipe bent into substantially inverted U-shaped form adapted to be secured at one leg of the U only and having a substantially vertical section, a horizontal section having one end integral with said vertical section and secured to the upper end thereof, and a depending section secured to the free end of the horizontal section; and stiffening members secured to said sections, said stiffening members having a trough-shaped portion and a projecting flange portion, the trough-shaped portion being secured over the pipe from the outside thereof with the flange portion projecting parallel to the sections inwardly of the U; and connection means securing the flange portions together adjacent the respective junction points of the vertical section, the horizontal section, and the depending section.

2. A car washing apparatus comprising a dolly having a substantially rectangular frame and a plurality of wheels secured to said frame to support the same for rolling movement over a surface; a fluid tank having a predetermined center of gravity secured to said frame, said tank being so located that the vertical projection of the center of gravity falls in the region between a longitudinal median line of the frame and one side thereof; a pump mounted on said frame; fluid connection means from said fluid tank to said pump; a driving motor mounted on said frame and operatively connected to said pump; means selectively connecting the driving motor to at least one wheel of the dolly; a spraying pipe having a substantially upright portion, a substantially horizontal portion secured to said upright portion at its upper end, and a depending portion secured at the upper end thereof to said substantially horizontal portion, the lower end of said depending portion being free to form an inverted U frame secured at one leg only to the frame, said spraying pipe having its upright portion secured to the other side of the dolly in substantially vertical direction so that the weight of the spraying pipe including the upright, the horizontal, and the depending portions will be counter-

balanced by the weight of the tank; and conduit means removably connecting said pump and said spraying pipe.

3. A car washing apparatus according to claim 2 wherein the horizontal portion is divided into a first pipe section and a second pipe section, and the second pipe section is of slightly smaller outside diameter than the inside diameter of the first pipe section; and a union is provided to join said sections together, said union having a pair of parts formed with cooperating faces and having one part mounted on the first pipe section and the other part on the second pipe section; said second section having a projecting stub extending through and beyond the part of the union associated therewith and disposed in telescoping relation within the inside of the first pipe section whereby mechanical strain due to the bending moment of the depending section is taken up by the projecting stub and mechanical strain is taken off the cooperating faces of the union.

4. A car washing apparatus according to claim 2 wherein in the upright portion of the spraying pipe is secured to the dolly for swinging movement about the axis of the pipe to provide for movement of the horizontal portion and the free depending portion secured thereto without disturbing the position of the dolly so that the spray pipe may be swung to be located in an upright plane substantially coinciding with the other side of the dolly.

5. A carwashing apparatus according to claim 2 including stiffening and spray directing members secured to the portions of the spraying pipe, said stiffening and spray directing members comprising a trough-shaped portion and a projecting flange portion, the trough-shaped portion being secured over the spray pipe from the outside thereof with the flange portion projecting parallel to the pipe portions inwardly of the U, and connection means securing the flange portions together adjacent the respective junction points of the upright pipe portion, the horizontal pipe portion and the depending pipe portion.

6. An independently movable car washing apparatus comprising a wheeled frame; a fluid tank mounted thereon, a spraying frame secured to said wheeled frame connected to said tank; wheel guide means to define the path of said wheeled frame and being adapted to cooperate with the wheels of the car to be washed and comprising a pair of substantially parallel elongated members defining a guide trough for the wheels of the apparatus; and locating shoes secured to one of said members opposite the side of the other member and extending toward the car to be washed and adapted to be removably placed against the wheel of the car to be washed, whereby, when the wheels on one side of the apparatus are disposed between said elongated members, and the locating shoes are placed against the wheels of the car to be washed, the apparatus may travel along the length of the car without danger of collision therewith.

7. An apparatus according to claim 6 wherein the locating shoes comprise a holding section extending transversely of the length of the elongated members; connection means associated with said elongated members and securing said holding section to one of said members; and a forked section extending substantially parallel to the length of said elongated members and secured to said holding section, and adapted to partly embrace a wheel of the car to be washed.

8. An apparatus according to claim 7 wherein the connection means are slidable along the length of the elongated member, whereby the locating shoes are adjustable for different lengths of wheel bases of cars to be washed.

9. An apparatus according to claim 6 including spacing means secured to said elongated members to maintain said members in predetermined, spaced parallel relation.
